Term of patent 14 years

Int. Cl. D25—02
U.S. Cl. D18—2 B

FIG. 1 is a fragmentary perspective view from below showing a decorative suspended ceiling embodying the invention, it being understood that the design repeats both laterally and longitudinally;

FIG. 2 is a fragmentary elevational view taken on the line 2—2 of FIG. 1;

FIG. 3 is a fragmentary sectional view taken on the line 3—3 of the FIG. 1; and

FIG. 4 is a fragmentary plan view taken from below showing the decorative suspended ceiling embodying the invention with several adjacent decorative panels and a decorative structural member located between each pair of panels.

The design of this invention is characterized in that each structural support member has an outer surface with a narrow ornamentation extending substantially the length of the support member and in that each decorative panel has an outer pile surface including four tapered side surfaces extending a substantial distance downwardly below the plane of the structural support members.

I claim:

The ornamental design for a decorative suspended ceiling, as shown and described.
